Attorney

UNITED STATES PATENT OFFICE.

WILBUR L. WALKER, OF LA GRANGE, ILLINOIS.

ADJUSTABLE TIEBAR FOR SWITCHES.

Application filed December 13, 1922. Serial No. 606,689.

To all whom it may concern:

Be it known that I, WILBUR L. WALKER, a citizen of the United States, residing at La Grange, in the county of Cook and State of Illinois, have invented certain new and useful Improvements in Adjustable Tiebars for Switches, of which the following is a specification.

My invention relates to railway track construction and more particularly to an adjustable tie bar for railway switches. It is quite desirable that railway switch connections, tie bars and the like be provided with means for adjustment to facilitate their installation and also to compensate for wear of the switch parts. It is essential, however, that such adjustment features or take up devices be of positive character, incapable of accidentally changing adjustment, yet easily and readily accessible and convenient for adjustment when a change is to be made.

The present form of tie bar adjustment contemplates two relatively adjustable members having interposed therebetween a number of interchangeable shims of various thickness the shims being enclosed or housed in such manner that they may not be accidentally disengaged or removed, thus insuring the safety of these connections.

The object of the invention is to simplify the structure as well as the means and mode of operation of adjustable connections applicable to railway switch connections and the like, which will not only be cheap in construction, but will be more efficient in use, positive in operation, capable of being easily and quickly adjusted, of increased durability and unlikely to get out of repair.

A further object of the invention is to provide such adjusting device, which while being easily accessible will be fully safeguarded against accidental disengagement and against any accidental change of adjustment.

A further object of the invention is to provide such adjustable connection having a comparatively wide range of adjustment, through a succession of small units of variation.

With the above primary and other incidental objects in view as will more fully appear in the specification, the invention consists of the features of construction, the parts and combinations thereof and the mode of operation, or their equivalents as hereinafter described and set forth in the claims.

In the accompanying drawings, wherein is shown the preferred, but obviously not necessarily the only form of embodiment of the invention, Fig. 1 is a perspective view of a portion of a railway rail and adjustable switch point, to which the adjustable tie bar connection forming the subject matter hereof has been applied. Fig. 2 is a side elevation partly in section, of the adjustable connection. Fig. 3 is an end elevation likewise partly in section of the tie bar and its connection. Fig. 4 is a detail perspective view of the engaging end of the tie bar and the adjusting shims and space block disconnected from each other. Figs. 5 and 6 are detail plan views showing different relative adjustments of the interconnected parts by transposition of the adjusting stem. Fig. 7 is a detail end elevation illustrating a modification of the construction previously described.

Like parts are indicated by similar characters of reference throughout the several views.

In the drawing 1 is the track rail and 2 the adjustable switch member movable in relation with the rail. Connected to the switch member 2 by the adjustable connection forming the subject matter hereof, is a transversely arranged tie bar 3. For the purpose of connecting this tie bar 3 with the switch member 2, there is provided a bracket bolted or otherwise secured to the switch member 2, comprising a T shaped head portion 4, from which projects the arm 5, formed integral with the head 4 and supporting a housing or keeper 6, within which the tie bar 3 extends. The head 4 of the bracket may be attached by suitable bolts 7, to the switch member 2. In the particular design illustrated the supporting arm 5 is provided with a strengthening rib by which the bracket is enabled to withstand severe strains and hard usage. The housing or keeper 6 is of recumbent U-shaped form, comprising top and bottom walls 6^a and 6^b, extending in substantially parallel spaced relation and interconnected at one edge as at 6^c, leaving the opposite lateral edge and the ends of the keeper or housing open. The intervening space within the housing or keeper 6 is such as to permit the free and easy adjustment of the bar 3 therewithin. That portion of the tie bar 3 within the housing or keeper is provided with an elongated rectangular opening 9, to receive a space block

10, and a plurality of interchangeable shims 11, which together completely fill the opening 9. For convenience of assembly outside the housing or keeper 6, the space block 10 and shims 11 are preferably provided with laterally projecting ledges or extensions 12, whereby the shims are of substantially T-shape. These ledges or extensions 12 will rest upon the tie bar 3 about the margins of the opening 9, thereby temporarily supporting the block and shims in adjusted relation until the bar with its collection of shims is inserted within the keeper or housing. The housing is of sufficient depth to accommodate the extension of the shims and block 10 above the top surface of the bar 3. The block 10 and the housing or keeper 6 are provided with holes 13 and 14 respectively, which register with each other whatever the relative adjustment may be. These registering holes 13 and 14 receive a coupling pin or bolt 15, which extends transversely through the housing or keeper 6, and through the interposed block 10 upon each side of which the interchangeable shims 11 are arranged to afford the desired degree of adjustment. It is quite obvious that so long as the shims and space block are enclosed within the housing or keeper, the shims cannot be displaced either accidentally or otherwise. The shims 11 being of such thickness and number as to completely fill the space 9 on opposite sides of the block 10 afford a positive connection between the block and the bar 3 in either direction. By removing the coupling pin or bolt 15, the bar with its collection of shims and the block 10 may be withdrawn from the keeper or housing 9, and the shims rearranged by transposing one or more shims from one side of the space block to the other, to afford different degrees of adjustment. While these shims may be provided in any number and any combination, for illustrative purposes only, a combination of five shims is suggested, having thickness varying by one sixteenth of an inch from a quarter inch to a half inch inclusive. Thus the five shims would be one quarter inch, five sixteenths, three eighths of an inch, seven sixteenths of an inch and one half inch respectively. By variously arranging such combination of shims on opposite sides of the space block 10 a range of adjustment at each end of the tie bar may be effected by sixteenths of an inch, from one sixteenth to one and three eighths inches, and by quarter inches from one and three eighths to one and seven eighths inches, while the throw of the switch may be varied from three inches to five and three quarter inches by variations of one sixteenth inch and from two and one half inches to six and a quarter inches by fourths of an inch. These dimensions are mentioned not with any intent of limiting the invention to specific

sizes or dimensions, but for illustrative purposes only, it being understood that the size and number of shims may be increased or diminished in accordance with varying conditions of use. 70

In lieu of the self supporting shims engaging the tie bar 3 by means of the extensions 12, such extensions or supporting ledges may be entirely omitted. In such case the lower side or bottom 6^b of the housing or keeper 6 may be extended laterally as at 16, Fig. 7, to form a temporary support for the bar 3 and shims, during the assembly of the parts in their relatively adjusted position after which the bar and assembled keeper may be shifted laterally upon such projecting lip or ledge 16 within the keeper or housing 6. 75

In Figs. 5 and 6 there are shown two different adjustments effected by transposition or the adjusting shims from one side to the other of the intermediate space block. 80

It will be obvious that by the construction described, the bar 3 will be positively connected with the switch member for movement in either direction at all times, yet the connection cannot become loosened by vibration and will not wedge nor stick to prevent adjustment when change becomes necessary. The adjustable parts are protected to some extent from weather and from tampering. 95

It will be understood that in the usual and ordinary application of the invention, an adjustable connection as here described will be provided at each end of the tie bars 3. This will enable either switch point to be adjusted in relation with the rail, independent of the other point, in order that the switch members may engage uniformly. It also enables the switch points to be relatively adjusted to bring them to proper gauge. 100

The supporting bracket comprising the head 4, arm 5, and housing 6 is a standard design of track member. This form of bracket is very generally used at the present time. The present invention is thus applicable to existing railway track work, without disarrangement of track by employing the existing brackets and substituting for the present tie bar connection, the interchangeable shim and adjustable block connection of the present construction. 110

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages. 115

While in order to comply with the statute the invention has been described in language more or less specific as to structural features, 120

it is to be understood that the invention is not limited to the specific details shown, but that the means and construction herein disclosed comprises the preferred form of several modes of putting the invention into effect and the invention is therefore claimed in any of its forms or modifications within the legitimate and valid scope of the appended claims.

10 Having thus described my invention, I claim:

1. In a construction of the character described, a recessed attachment bracket, a bar longitudinally adjustable within the recess 15 of said bracket having an elongated opening in the portion of the bar contained within the recess of the bracket, a member operatively engaged with the bracket extending within the opening in the bar, and a plurality 20 of interchangeable shims of different thickness inserted within the opening in the bar beside said bracket engaging portion, and within the recess of the bracket whereby the bracket overhangs the shims to prevent 25 their displacement from the opening in the bar.

2. In a construction of the character described, a switch member, a tie bar adjustably connected thereto, a recessed bracket 30 carried by the switch member within the recess of which the tie bar extends, and a series of interchangeable shims having engagement with the tie bar within the recess of the bracket for maintaining the bar in different positions of adjustment in relation 35 with the bracket, said shims being held against displacement by said bracket.

3. In a construction of the character described, a tie bar having an opening therein, 40 a connection for said tie bar extending through said opening, a plurality of interchangeable shims also located within said opening, and a housing enclosing the shims to prevent displacement of the shims from the opening in the tie bar.

4. In a construction of the character described, two relatively adjustable members one of which is provided with a recess within which the other member extends, a plurality 50 of interchangeable shims also located within said recess to complete the filling of the same, and a housing enclosing the shims to prevent their displacement from said recess.

5. In a construction of the character described, a recessed bar, a thrust member extending within the recess of the bar, a plurality 55 of interchangeable shims arranged beside said thrust member within said recess, and an enclosure for the recessed portion of the bar and the shims preventing the displacement of the shims from said recess.

6. In a construction of the character described, an adjustable bar having an elongated opening therein, a second member

overlapping the elongated opening in the bar, a coupling member carried by the overlapping member, and extending within the said opening in said bar and a series of removable shims engaged in said opening beneath the overhanging member to differentially position the coupling member within the elongated opening.

7. In a construction of the character described, a bifurcated member, a second member extending between the furcations of the first member, a coupling member extending thru the furcations of the first member and through the interposed second member, and a plurality of interchangeable shims located in said second member beside the coupling member and overhung by the furcations of the first member to prevent their displacement.

8. In a construction of the character described, two overlapping relatively adjustable members having a slot and pin connection one with the other and a series of interchangeable shims interposed in the slot to variously limit the adjustment of the slot and pin connection, said shims being overlapped by one of said members to prevent their displacement from the other.

9. In a construction of the character described, two relatively adjustable overlapping members, a coupling means between said members and a plurality of interchangeable shims which by their transposition vary the relation of the coupled members, said shims being held against displacement by the overlapping relation of the members.

10. In a construction of the character described, a bar having an elongated opening, a thrust member engageable within said opening, a plurality of shims insertable within the opening beside the thrust member to afford variable abutment for the thrust member in either direction, means for preventing the displacement of the shims when in operative position, and means for temporarily supporting the shims in their assembled relation prior to the application of the anti-displacement means thereto.

11. In a construction of the character described, a bar having an elongated opening therein, a thrust member engageable within said opening, a plurality of substantially T-shaped shims insertable within the opening, beside the thrust member, to afford variable abutment for the thrust member, said shims being supported in assembled relation by the engagement of the lateral projections of said T-shaped shims with the bar, and means for preventing the displacement of the shims from said opening.

12. In a construction of the character described, a bar having therein an elongated opening, a thrust member engageable within the opening, and a plurality of shims in-

sertable within said elongated opening beside the thrust member to afford a variable abutment for said thrust member, and means overhanging said shims when in operative position to prevent their displacement from the opening in said bar.

In testimony whereof, I have hereunto set

my hand this 5 day of December, A. D. 1922.

WILBUR L. WALKER.
